[57] CLAIM

The ornamental design for a boat hull, substantially as shown and described.

DESCRIPTION

FIG. 1 is a bottom perspective view of a new boat hull design of the present invention.

FIG. 2 is a side elevational view of the boat hull of FIG. 1 with lines thereon indicating stations 0 through 10 at which the half sections of FIG. 6 are taken.

FIG. 3 is a bottom plan view of the boat hull of FIG. 1. FIG. 4 is a front elevational view of the boat hull of FIG. 1.

FIG. 5 is an aft elevational view of the boat hull of FIG. 1.

FIG. 6 shows hull half sections as traditionally prepared by naval Architects with the station numbers thereon corresponding to the station numbers of FIG. 2.

FIG. 7 is a perspective view taken from below the hull of the present invention and taken generally from a forward aspect thereof.
